KEY CASE

Robert C. Legat, New Britain, Conn., assignor to
The G. E. Prentice Mfg. Co., Kensington, Conn.,
a corporation of Connecticut

Application August 19, 1947, Serial No. 769,371

5 Claims. (Cl. 70—456)

1

This invention relates to key cases and has for its principal object the provision of an improved key holder for such cases. More specifically the invention contemplates providing a key holder which is sturdy in construction though economical to manufacture, which enables the keys to be readily selected for use or removed individually from the holder, and which reduces wear on the casing to a minimum.

Other objects of the invention, as well as the novel features of its construction, will become apparent from the following description when read in connection with the accompanying drawings, in which Fig. 1 is a front elevational view of the holder showing it mounted on a side of a casing; Fig. 2 is a side elevational view of the construction shown in Fig. 1; Fig. 3 is a view similar to Fig. 1 but showing the locking levers for the key hooks in open position; Fig. 4 is a side elevational view of the structure shown in Fig. 3; Fig. 5 is a front elevational view of the main plate of the holder and Fig. 6 is a sectional view taken along the line 6—6 of Fig. 5.

In the drawings, the reference numeral 10 indicates one side of the casing which may be made of leather or any other suitable material and of such size as to accommodate keys hanging on the hooks 11. The casing may be closed by means of a slide operable fastener extending around three of its sides, as is well-known in the art. The hooks 11 are pivotally supported on a holder composed of a flat plate 12 made of sheet metal and bent along its top edge into the form of a U-shaped channel portion 13, the major portion of such channel portion projecting forwardly of the front face of the plate, while the upper free edge portion 14 thereof extends beyond the rear face of such plate as can be seen more clearly in Figs. 2, 4 and 6 of the drawings. The rearwardly projecting edge portion 14 of the plate 12 maintains the casing spaced from the area defined by the channel portion 13 and thereby prevents the enlarged ends 15 of the hooks 11 from wearing out the material of the casing while the keys attached to such hooks are manipulated in the use of the holder. The edge portion 14 extends continuously across the top of the holder (note Fig. 5) and thereby also functions as a stop to limit the movement of the key hooks 11 in an upward or outward direction.

Formed in the upper portion of the plate 12 are two sets 16 and 17 of cutouts or apertures, each aperture being constituted of a slot-like portion 18 having parallel sides and extending from a point just below the channel portion 13, trans-

2

versely through the material of such channel portion and to the edge portion 14. The lower end of the slot portion 18 of each aperture communicates with an offset enlarged opening 19 which is of a size to permit the free insertion therethrough of an enlarged end 15 of a key hook, it being understood that the width of each slot portion 18 is less than the transverse width of such end 15, but greater than the transverse width of the key hook adjacent to its enlarged end 15. Thus, while the enlarged end 15 of a key hook may be readily inserted through the opening 19 of each aperture, it cannot be removed outwardly through the slot portion 18 of such aperture 15 though the hook may be moved freely along the slot portion 18 and pivotally relative thereto. In this connection, it might also be pointed out that the edge portion 14 limits upward movement of the enlarged end 15 in the slot portion 18 and the casing 10 restricts the inward movement of such end relative to the plate 12. It will also be noted that the openings 19 of the set of apertures 16 are disposed in opposed relation to the openings 19 of the set of apertures 17, the openings in each set being offset toward the adjacent side edge of the plate 12. While this arrangement is shown for six key hooks, it will also hold true if the holder is constructed for four or eight key hooks.

Arranged along the bottom edge of the plate 12 are two series 20 and 21 of apertures, each aperture in the series 20 being aligned with the enlarged opening of an aperture 16 and a section of the channel portion adjacent to the slot portion 35 of such aperture 16, and each aperture in the series 21 being aligned with the enlarged opening of an aperture 17 and a section of the channel portion adjacent to the slot portion of such aperture 17. Hingedly mounted on the bottom edge 40 portions of the plate which define the bottom edges of the apertures 20 and 21 are a plurality of levers 22 arranged in two sets of three levers and each set being separated by a rigidifying plate 22' overlying and secured to the central transverse portion of plate 12, such plate 22' being substantially similar in appearance to the levers 22. Each of the levers 22 has a body portion 23 that extends up to the lower end of the slot portion 18 of its associated aperture 16 or 17 when 45 the lever is in closed position and of a width such that the combined, overall width of each set of such levers completely conceals the underlying portion of plate 12 on one side of plate 22'. The upper ends 24 of the levers 22 and plate 55 22' are reduced in width so as not to cover the

slot portions 18 of the apertures 16 and 17 when the levers 22 are closed. The upper portions of the lever ends 24 are bent into a form substantially similar to that of the channel portion 13, but have a degree of curvature slightly less than the latter so that such portions can be pressed into locked position on those sections of the channel portion 13 adjacent to the slot portions 18 and which they overlie. The material of the upper end 24 of each lever is stamped to provide a finger-nail tab 25 by which the lever can be unlocked from the channel portion 13 simply by lifting such end from engagement with the latter. Intermediate the series of apertures 20, 21 and the lever ends of the apertures 16, 17 are a pair of apertures 26 through which extend rivets that secure the plate 12 to the casing 10.

It will be understood from the foregoing that the levers 22 of the holder are normally in closed position with their upper ends 24 in locked engagement with the channel portion 13 of the plate 12, as shown in Figs. 1 and 2 of the drawings. In this condition of the parts, the body portions 23 of the levers completely cover the openings 19 of the apertures 16, 17 and thereby prevent the removal of the key hooks 11. The key hooks 11 however, are free to pivot in the slot portions 18 of the apertures to enable the keys connected thereto to lie flat in the casing 10 or to enable the keys to be moved outside the upper end of the casing for use. The outer surfaces of the levers 22 and plate 22' may be coated to give to the holder an attractive appearance, and provided with an index indicating the place where the particular key associated therewith is to be used. When it is desired to remove any key hook 11 with its associated key, either to use the key more conveniently or to replace it with another key, all that is necessary is to lift the lever from its locking engagement with the channel portion 13, through the fingernail tab 25, thus exposing the whole of their associated aperture 16 or 17, and then moving the enlarged portion 15 along the slot portion 18 of such aperture, into the opening 19 thereof, whereupon the hook can readily be removed from the holder. To return the hook and its key to the holder, these operations in reverse are carried out. It will also be noted that in the use of this device, the material of the casing underlying the holder cooperates with the latter to maintain the enlarged portions 15 of the hooks in position in the channel portion 13, the casing material however, permitting the removal and proper insertion of a hook when so desired.

I claim:

1. A key holder comprising a plate having at its upper end a longitudinally extending channel-shaped portion projecting outwardly from the front face of said plate, said channel portion being divided into a series of sections by a plurality of slots which extend transversely of such plate to points spaced below said channel portion, each of said slots communicating at its lower end with an enlarged opening in such plate and through which the head of a key hook may be passed into the area defined by said channel portion, and a plurality of levers pivotally connected to the lower edge of said plate, said levers being constructed to overlie said enlarged openings to lock the key hooks in position on said holder, but to leave exposed said slots to permit of free pivotal movement of the hooks about their head portions, and locking means on each of said levers adapted to

cooperate with said channel portion to lock said levers in said overlying position.

2. In a keyholder comprising a plate having at its upper end a longitudinally extending channel-shaped portion projection outwardly from the front face of said plate, said channel portion being divided into a series of sections by a plurality of slots which extend transversely of such plate to points spaced below said channel portion, each of said slots communicating at its lower end with an enlarged opening in such plate and through which the head of a key hook may be passed into the area defined by said channel portion, and a plurality of levers pivotally connected to the lower edge of said plate, said levers being constructed to overlie said enlarged openings to lock the key hooks in position on said holder, but to leave exposed said slots to permit of free pivotal movement of said hooks about their head portions, the upper ends of said levers being bent into a form substantially similar to that of said channel-shaped portion but defining an area slightly less than the latter so that such upper ends of the levers can be pressed into locked position on said channel-shaped portion, and means on the upper end of each of said levers to enable said lever to be manually unlocked from said channel-shaped portion.

3. In a keyholder comprising a plate having at its upper end a longitudinally extending channel-shaped portion projecting outwardly from the front face of said plate, said channel portion being divided into a series of sections by a plurality of slots which extend transversely of such plate to points spaced below said channel portion, each of said slots communicating at its lower end with an enlarged opening in such plate and through which the head of a key hook may be passed into the area defined by said channel portion, and a plurality of levers pivotally connected to the lower edge of said plate, said levers having flat body portions which overlie the front face of said plate below said channel-shaped portion and overlie said enlarged openings to lock the key hooks in position on said holder, the upper ends of said levers being positioned in overlying relation on said channel-shaped portion adjacent to the transverse slots thereof and being bent into a form substantially similar to that of said channel-shaped portion but such that the upper ends can be pressed into locked position on said channel-shaped portion, and a part connected to the upper end of each of said levers to enable such levers to be manually unlocked from said channel-shaped portion and swung away from such plate to uncover said enlarged openings.

4. In a keyholder comprising a plate having at its upper end a longitudinally extending channel-shaped portion projecting outwardly from the front face of said plate, said channel portion being divided into a series of sections by a plurality of slots which extend transversely of such plate to points spaced below said channel portion, each of said slots communicating at its lower end with an enlarged opening in such plate and through which a key hook may be passed into the area defined by said channel portion, said enlarged openings being wholly located below said channel-shaped portion and being offset from their associated slots, and a plurality of levers pivotally connected to the lower edge of said plate, said levers having flat body portions which overlie the front face of said plate below said channel-shaped portion and overlie said enlarged openings to lock the key hooks in

position on said holder, and said body portions substantially concealing the front face of said plate below said channel-shaped portion, the upper end of each of said levers being reduced in width and being positioned in overlying relation over that section of the channel-shaped portion located above its associated enlarged opening and adjacent to the slot connected with such opening, the upper ends of said levers being bent into a form substantially similar to that of said channel-shaped portion but such that the upper ends can be pressed into locked position on said channel-shaped portion, and a part connected to the upper end of each of said levers to enable such levers to be manually unlocked from said channel-shaped portion and swung away from such plate to uncover said enlarged openings.

5. A key holder comprising a plate having at its upper end a longitudinally extending channel-shaped portion projecting outwardly from the front face of said plate, said channel portion being divided into a series of sections by a plurality of openings, each of such openings having a slot-like upper portion extending transversely of said channel portion to a point spaced therebelow and an enlarged lower portion in the body of said plate to permit the head of a key hook to pass therethrough into the area defined by said channel portion, each of the enlarged lower portions of the openings being offset from its associated slot-like upper portion and located below a section of said channel portion forming one

side of such upper portion, and a plurality of levers pivotally connected at their lower ends to the lower edge of said plate, said levers being constructed to overlie the enlarged lower portions of the openings to lock the key hooks in position on the holder, but to leave exposed the slot-like upper portions of the openings to permit of free pivotal movement of the hooks about their head portions, and locking means on the upper end of each of said levers adapted to interlock with the section of said channel portion above the offset lower portion of the opening which such lever overlies to lock such lever in such overlying position.
